UNITED STATES PATENT OFFICE.

STEPHEN A. KISS, OF YONKERS, NEW YORK.

LETTER-BOX AND COLLECTING-POUCH.

1,102,760.

Specification of Letters Patent.

Patented July 7, 1914.

Application filed April 6, 1914. Serial No. 829,900.

To all whom it may concern:

Be it known that I, STEPHEN A. KISS, a subject of the King of Hungary, and resident of Yonkers, in the county of West-
5 chester and State of New York, have invented certain new and useful Improvements in Letter-Boxes and Collecting-Pouches, of which the following is a specification.

10 The present invention relates to letter boxes and collecting pouches or bags co-
operating therewith.

One of the objects of the invention is to
15 so construct these two elements that, on at-
taching the collecting bag to the letter box,
the former is automatically opened, the bot-
tom of the letter box being caused to swing
around its hinges by means carried by the
20 bag, whereby the letters or other mail mat-
ter are emptied into the bag.

With these and other objects in view,
which will more fully appear as the nature
of the invention is better understood, the
25 same consists in the combination, arrange-
ment and construction of parts hereinafter
fully described, pointed out in the appended
claims and illustrated in the accompanying
drawings, it being understood that many
30 changes may be made in the size and pro-
portion of the several parts and details of
construction within the scope of the appended
claims without departing from the spirit
or sacrificing any of the advantages of the
invention.

35 One of the many possible embodiments of
the invention is illustrated in the accom-
panying drawings, in which:

Figure 1 is a vertical central section taken
40 through a letter box constructed in accord-
ance with the present invention; Fig. 2 is
a section taken on line 2—2 of Fig. 1; Fig.
3 is a section taken on line 3—3 of Fig. 1;
Fig. 4 is a sectional view of a detail of con-
45 struction; Fig. 5 is a side elevation of the
said detail; Fig. 6 is a plan view thereof;
Fig. 7 is a front elevation of a key for open-
ing the box; Fig. 8 is a plan view thereof;
Fig. 9 is a side elevation of the same; Fig.
50 10 is a plan view of the collecting pouch
or bag; Fig. 11 is a bottom plan view of
the frame of the same; Fig. 12 is a section
taken on line 12—12 of Fig. 10; Fig. 13 is
a section taken on line 13—13 of Fig. 10;
Fig. 14 is a section taken on line 14—14 of
55 Fig. 10; Fig. 15 is a plan view of a key for

opening the pouch; and Fig. 16 is a front elevation of said key.

The letter box is illustrated in Figs. 1
to 6, inclusive, in which the numeral 20 in-
dicates the casing of the box, preferably a
double walled sheet metal receptacle, hav-
ing a cover 21, preferably sloping down-
ward on all sides and projecting beyond the
vertical walls of the casing to cause rain,
water, etc., to run off the same. The cas-
ing is provided in its vertical side walls
with the usual slots 22 for the introduction
of letters or other mail matters, said slots
being normally closed by hinged flaps 23.
The bottom 24 of the box is pivoted at 25
to the sides of the casing 20. This bottom
is also double walled and incloses, like the
parallel sections of the walls of the casing,
an insulating material, denoted by the nu-
meral 26. The front edge 27 of the bottom
is provided with a horizontal projection 28,
that is engaged by a plurality of locking
bolts 29, which are slidably arranged in
guides 30. Each of these locking bolts is
connected by a link 31 with an actuating
pin 32, the said pins being disposed verti-
cally in apertures 33 in the front wall of
the casing. The apertures 33 are, prefer-
ably, of different sizes and of different con-
figurations for a purpose hereinafter to be
described. Springs 35, disposed in the front
wall of the casing 20, bear against the lock-
ing bolts 29, and serve to hold the latter in
their projected positions, in which they keep
the bottom of the letter box closed.

In the lowermost portions of the sides
of the casing are provided grooves 36,
preferably, of quadrangular cross section.
These grooves are disposed below the bottom
24 and extend throughout the lengths of
45 said sides, merging into slots 37 of the same
lengths, the latter extending through the
lower faces of said sides. In each groove
36 is disposed a stop 38, that is preferably
attached to the rear wall of the casing and
provided in its front edge with notches 39
in the same manner and for the same pur-
pose as the bits of keys are provided with
wards. The purpose of these stops will be
explained hereinafter.

It is to be observed that any suitable num-
ber of locking bolts may be provided upon
the box. In the case illustrated in the draw-
ings four have been shown. If it is in-
tended to open the box for repairing pur-
110

poses or for inspection, the repairman or inspector may do so by means of the key illustrated in Figs. 7 to 9, inclusive, of the drawings. This key comprises a base plate 40, having four upwardly projecting lugs 41, the sizes and configurations of which correspond to those of the apertures 33. By inserting the lugs into the said apertures and forcing the same upward, the actuating pins 32 are caused to move upward, thereby retracting the locking bolts 29 against the action of their springs 35 and releasing thus the bottom 24 of the box.

The collecting pouch is illustrated in Figs. 15 to 14, inclusive, and comprises a quadrangular frame 42, to which is fastened by rivets 43, or otherwise, a pouch or bag 44. To this frame is pivoted at 45 a cover frame 46, to the latter being fastened by rivets 47, or otherwise, and by a string 48 a covering 49 of leather or of other suitable material. The front edge of the cover frame is provided with a horizontally extending projection 50, below which are adapted to project lugs 51 of bars 52, which are shiftably disposed in grooves 53 in the side sections of the frame 42. Springs 54, disposed in a groove 55 in the front section of the frame 42, keep the lugs in their projected positions, in which they hold the cover of the pouch in its closed position. In the rear ends of the bars 52 are formed notches or wards 56, corresponding to the notches 39 in the stops 38. In the groove 55 is disposed a plate member 57, carrying upon its upper face pins 58, which are adapted to project through apertures 59 in the front portion of the frame 42. The sizes and configurations of the pins 58 correspond to those of the apertures 33 in the casing of the letter box, and the location of the pins 58 is such that they register with the apertures 33 in the letter box when the collecting pouch is put, in a manner hereinafter to be described, in position upon the said letter box. A spring 60, bearing against the plate 57 and the front portion of the frame 42, keeps the pins 58 normally within the said frame. Lugs 61, disposed upon the underface of the plate member 57, project through openings 62 in the front portion of the frame 42 below the lower face of the latter, and serve as means, whereby the said plate member 57 may be raised and the pins 58 projected through the apertures 59. The side bars of the frame 42 fit the grooves 36 in the side walls of the casing of the letter box.

To the cover frame 46 are attached straps 63, which project through openings 64 in the frame 42. The purpose of this arrangement will be described hereinafter.

In Figs. 15 and 16 a key for opening the pouch is illustrated, said key comprising a bar 65, that is provided with fingers 66, which extend at right angles to the bar 65,

said fingers being provided with notches or wards 67, corresponding to the wards 56 above described. If it is intended to open the pouch, the fingers 66 of the key are inserted into the grooves 53 and engaged with the bars 52 therein. By forcing the said bars toward the front end of the bag frame 42, the lugs 51 are disengaged from the cover frame 46, which will then drop and permit of access to the interior of the pouch. To close the pouch, the cover frame is raised by means of the straps 63 until the lugs 51 are engaged with the projection 50 thereof.

The operation of these devices is as follows: In order to empty the contents of the letter box into the collecting pouch, the mail collector seats the rear ends of the side bars of the pouch frame 42 into the grooves 36 in the sides of the letter box, and pushes the pouch frame toward the rear wall of the said box, whereby the stops 38 in the grooves 36 engage with the bars 52 in the grooves 53 in the pouch frame and shift the said bars against the action of the springs 54, thereby disengaging the lugs 51 from the cover frame 46. The cover frame drops thus by its own weight into the pouch. When the pouch frame is in proper position upon the letter box, the apertures 59 in the pouch frame 42 register with the apertures 33 in the front wall of the letter box. When, therefore, the operator takes hold of the lugs 61 and thereby forces the plate number 57 upward, the pins 58 will shift the actuating pins 32 in the letter box upward, thus retracting the locking bolts 29 and releasing the bottom 24 of the letter box, which by its own weight drops into the pouch. The letters, or other mail matters, within the letter box will then drop into the collecting pouch. After this, the operator takes hold of the straps 63. By pulling the said straps upward, both the cover frame 46 of the collecting pouch and the bottom 24 of the letter box are raised and closed. The collecting pouch is then withdrawn from the letter box.

To the lower edge of the front wall of the letter box may be pivotally attached a narrow strip 68, which normally conceals the bottom of the box from view, and at the same time gives a finished appearance to the said box.

What I claim is:—

1. In an apparatus for receiving and collecting mail, the combination with a letter box having a hinged bottom, of a plurality of locking bolts in said box engaging said bottom for holding the same in closed position, the side walls of said box being provided at their lower ends with grooves extending therethrough, a stop disposed in each groove, a mail bag comprising a frame, the side portions of which are adapted to be seated in said grooves, a bar shiftably

disposed in each of said side portions provided with lugs, a cover upon said bag held in closed positions by said lugs, said lugs being automatically disengaged from said 5 cover by the said stops acting upon said bars when the side portions of said frame are pushed into the grooves in said side walls, and means upon said bag frame for retracting said locking bolts when said bag 10 is in proper position upon said box.

2. In an apparatus for receiving and collecting mail, the combination with a letter box having a hinged bottom, of a plurality of locking bolts in said box engaging said 15 bottom for holding the same in closed position, actuating pins connected with said locking bolts, the side walls of said box being provided at their lower ends with grooves extending therethrough, a stop disposed in each groove, a mail bag comprising 20 a frame, the side portions of which are adapted to be seated in said grooves, a bar

shiftably disposed in each of said side portions provided with lugs, a cover upon said bag held in closed positions by said lugs, 25 said lugs being automatically disengaged from said cover by the said stops acting upon said bars when the side portions of said frame are pushed into the grooves in said side walls, a plurality of shiftable pins 30 upon said bag frame in registering position with said actuating pins when said bag is in proper position upon said box, and means for shifting the pins upon said bag frame and thereby said actuating pins, whereby 35 said locking bolts are retracted.

Signed at New York, in the county of New York and State of New York, this 10th day of March, A. D. 1914.
